UNITED STATES PATENT OFFICE.

JOSEPH K. ALLISON, OF IOWA FALLS, IOWA.

PNEUMATIC NECKTIE.

1,347,359.

Specification of Letters Patent. Patented July 20, 1920.

Application filed January 15, 1920. Serial No. 351,676.

To all whom it may concern:

Be it known that I, JOSEPH K. ALLISON, a citizen of the United States of America, residing at Iowa Falls, in the county of 5 Hardin and State of Iowa, have invented new and useful Improvements in Pneumatic Neckties, of which the following is a specification.

The object of the invention is to provide 10 a necktie of the makeup type as of the four-in-hand form wherein a smooth and neat appearance thereof may be maintained or reproduced after protracted use of the tie, without the necessity of laundrying or pressing 15 the same and hence without the incidental inconvenience of disconnecting the parts of the same or removing them from their supporting cards or backing elements, and with this object in view the invention 20 consists in a construction and combination of parts of which a preferred embodiment is shown in the drawings wherein:

Figure 1 is a front view of the tie.

Fig. 2 is a vertical sectional view of the 25 same.

Fig. 3 is a detail view of the collar button clamp and inflation valve.

The tie consists essentially of a base or back 10 of cardboard or similar relatively 30 stiff material to which is attached the fabric facing 11 representing the tie proper and also carrying the tabs 12 for engagement with the collar of the wearer, and interposed between the base or backing and the facing 35 is an inflatable sack or lining 13 of rubber or similar flexible material adapted for holding air which may be introduced through the inflation tube 14 fitted with a flap valve 15, said tube being in the form 40 of a hollow rivet as shown clearly in Fig.

2 to serve as a means of attachment to the base or backing 10 of the collar button clamp 16. As shown the fabric facing material should be attached at its edges to the base or backing (see Fig. 2) to the end that it 45 serves as a means of limiting the inflation of the sack or bulb 13, and at suitable points the facing may be provided with pads 17 for engagement by cravat pins or the like without involving the puncturing of the sack. 50

Obviously when the tie becomes rumpled or creased it may be restored to its original condition by reinflation to the end that the facing material is held in proper shape determined by its points of attachment to the 55 base or backing, and furthermore it is obvious that the facing material may be renewed or replaced from time to time to vary the appearance of the tie or to correspond with changes in the styles thereof or to 60 suit the taste of the wearer.

What is claimed is:

1. A necktie having a base or backing and a flexible facing carried thereby, and an inflatable sack or lining interposed between 65 said base or backing and the facing.

2. A necktie having a base or backing and a fabric facing secured at its edges to the base or backing, and an inflatable sack or lining interposed between said elements, 70 the facing being provided with a pad for engagement by a cravat pin.

3. A necktie having a base or backing and a fabric facing carried thereby, an inflatable sack or lining interposed between 75 the base and said facing, and a valve inflation tube mounted in the base or backing and carrying a collar button clamp.

In testimony whereof I affix my signature.
JOSEPH K. ALLISON.
